FLUID CONTROL DEVICE

Alphonse F. Pieper, Brighton, N. Y.

Application February 3, 1937, Serial No. 123,781

7 Claims. (Cl. 128—224)

The present invention relates to a fluid control device such, for example, as a syringe and has for its object to provide in a device of this class combined structural units which can be readily assembled and separated from time to time to permit one or more of the units to be sterilized when desired and which when connected cooperate to afford an efficient and dependable fluid control device for the purpose intended.

10 A further object of the invention is to provide in a syringe of the present type an improved arrangement of parts by which the construction is simplified and the cost of manufacture reduced.

15 A further object of the invention is to provide a syringe including a casing having a nozzle thereon and a complete detachable interiorly disposed unit for delivering fluid to the nozzle, including relatively movable parts for controlling the flow of the fluid.

20 A further object of the invention is to provide in a syringe of the class described a casing having a rotary withdrawable fluid supply unit therein, comprising relatively movable sections and 25 valve means actuated by effecting relative movement between the sections by the use of suitable operating means on the casing, and in which arrangement improved means is provided for retaining the unit within the casing which can 30 be quickly and conveniently released without the use of tools to free the unit for withdrawal from the casing.

To these and other ends the invention resides in certain improvements and combinations of 35 parts, all as will be hereinafter more fully described, the novel features being pointed out in the claims at the end of the specification.

In the drawings:

40 Figs. 1 and 2 constitute longitudinal sections through a syringe embodying one form of the invention;

45 Fig. 3 is a fragmentary part sectional elevation showing the stop collar for the valve operating lever adjusted to a different position from that shown in Fig. 1;

Fig. 4 is a longitudinal section of the casing shown in Figs. 1 and 2 with the inner tubular unit removed therefrom;

50 Fig. 5 is a view of the detachable tubular unit shown removed from the casing;

Fig. 6 is a view of the unit shown in Fig. 5 looking from the right thereof, and

55 Fig. 7 is a transverse section on line 7—7 of Fig. 2.

The same reference numerals throughout the several views indicate the same parts.

The present syringe is of the class adapted for connection with a liquid or fluid supply source under pressure and in which the injection of the 5 liquid or fluid is effected by the pressure in the system, the syringe being adapted for connection with either a warm or cold water supply source.

Referring to the drawings, the syringe comprises a body portion designated generally by the 10 reference numeral 10 and includes a casing 11 having a recessed head 12 on its outer end provided with any suitable type of nozzle such, for example, as the tube 13 connected with the head by a suitable coupling 14. The head is provided 15 with a passage 15 within which is screwed the outer end of a relatively short tube or tubular section 16 in free communication with the nozzle and disposed within the recess 12a of the head, as shown in Fig. 1.

20 Screwed on or otherwise secured upon the inner end of the casing is a support 17 for the removable unit 18 disposed within the casing for delivering fluid to the nozzle through the tube 16. The removable unit includes a plurality of tubular sections such, for example, as the relatively 25 movable outer and inner sections 19 and 20, respectively. The inner unitary section 20 is preferably formed of three suitably connected parts or members comprising the inner and outer members 21 and 22 and the intermediate member 22a, Figs. 5 and 6, the inner member being preferably 30 screwed upon the intermediate member and the outer member secured upon the intermediate member by means of the screws 23. The intermediate member 22a is provided with a recess 24 communicating with a bore 25 within which is secured the inner end of a tube 26, the outer end of which extends within the bore 27 of the outer tubular section 19, as shown in Fig. 1. Thus it 35 will be seen that the detachable tubular unit 18 will be provided with a continuous centrally disposed fluid passage therethrough for the delivery of the fluid or liquid to the nozzle through the relatively short tube 16 fixed upon the casing.

40 The means for controlling the flow of the fluid through said tubular unit comprises a valve 28 normally closing the bore 25 of the member 22a and having a tapered portion 29 extending within said bore to afford a gradual increase in the flow 45 of the fluid when moving the valve to full open position. The valve is provided with a holder 30 in engagement with which is a spring 31 for normally maintaining the valve in closed position. The spring is preferably supported within 50 55

the recess 24 by a member 32 threaded therein and having an opening 32a for the passage of the fluid thereto.

The fluid is delivered to the recess through a suitable coupling 33 threaded within the intermediate portion 22a of the tubular section 20, the coupling having a reduced portion 33a for the reception of a flexible supply tube or conduit 34 adapted for connection with any suitable liquid or fluid supply source, not shown.

The valve is provided with an operating stem 35 which extends through the tubular member 26 and into the bore 27 of the outer tubular section 19, the stem having an enlarged portion 36 thereon, as shown in Fig. 1. A tubular valve actuating member 37 is threaded within the central portion of the outer tubular section 19 and extends into the bore 27 of said section for engagement by the enlarged portion 36 of the valve stem upon movement of the section 19 inwardly of the casing 11 to the position shown in Fig. 3 whereby to effect opening of the valve. Adjustment of the valve actuating member 37 to regulate the extent of the movement of the valve can be readily effected by inserting a screwdriver within the bore 27 and using it to turn the actuating member to vary the distance between the latter and the part 36 of the valve stem as may be required.

30 A spring 38 surrounding the tube 26 serves to normally maintain the tubular section 19 at its outermost position at which it is held by engagement of the heads of the screws 39 thereon with the walls of the outer member 22 of the detachable section 20, the heads of the screws engaging said member within the slots 40 formed therein, as shown in Fig. 1, and being movable within the slots upon inward movement of the section to the position shown in Fig. 3 for the purpose of opening the valve.

Suitable packing 41 is disposed within the recesses formed in the opposite ends of the tubular section 19 for insuring liquid-tight joints between said section and the tubes 16 and 26 telescoped within the section, the packing being compressed and held in position by the members 42 threaded within the opposite ends of the section, as shown in Fig. 1.

Means for moving the section 19 to effect opening of the valve preferably comprises a finger lever 43 having its lower end disposed between the ends 44 of a band 45 which is clamped upon the tubular casing 11 by means of a bolt or pin 46 forming a pivot upon which the lever is adapted to swing. The lever carries a lateral projection 47 extending through an opening 48 in the wall of the casing 11 and engaging a shoulder or cam 49 on the tubular section, with the result that when the lever is swung inwardly toward the casing from the position shown in Fig. 1 the tubular section will be moved inwardly of the casing to effect opening of the valve, the section being returned to normal position by the spring 38 upon releasing the lever. Normally the extent of the inward movement of the section 19 and the resulting movement of the valve is limited by the contacting of the portion 43a of the lever with a collar 50 on the casing 11 when the collar is in the position shown in Fig. 1. The collar, however, is threaded upon a ring 51 fixed on the casing so that the collar may be adjusted by rotation from the position shown in Fig. 1 to that shown in Fig. 3 when it is desired to open the valve to the full extent to obtain a maximum flow of the liquid through the nozzle, the ring

being cut away at 52 to allow for an increase of the movement of the lever and a consequent increase in the movement of the tubular section 19 and the valve operating stem 35.

The means for holding or maintaining the detachable unit 18 within the casing 11 preferably comprises a resilient element 53 in the form of a leaf spring disposed within a groove 54 formed in the wall of the innermost member 21 of the unit, the spring being secured within the groove by a screw 55 extending within the wall of the member 21, Fig. 2. Application of the screw can be effected by the use of a screw driver which may be inserted through an opening 56 in the wall of said member to engage and turn the screw. The opposite end of the spring is provided with a laterally projecting locking part 57 extending through an opening 58 in the wall of the member 21 and into an annular groove 59 formed in the wall of the supporting member 17 which affords a track-like shoulder 60 on which the part 57 is adapted to rest and by which the detachable unit 18 is supported within the casing. Secured on the spring 53 between the ends thereof is an operating button or member 61 which extends through an opening 62 in the wall of the member 20, as shown in Fig. 2. By pressing inwardly on the button with the thumb or finger the locking part 57 can be moved inwardly and out of engagement with the shoulder 60 thereby releasing the detachable unit 18 for withdrawal from the casing, thus freeing the latter for insertion within a suitable sterilizer in which not only the casing will be sterilized but likewise the operating lever, the nozzle, and other parts attached to the casing.

It will be noted that the free end of the support 17 is provided with an inner beveled or cam face 63 on which the locking member 57 will ride when moving the tubular unit 18 into final position within the casing and by which said locking member will be moved inwardly under the tension of the spring 53 which will serve to snap the locking member into the groove 59 when it clears the cam face 63.

Furthermore, by making the groove and cam face continuous, the unit 18 can be readily moved to final position within the casing without having to rotate it therein to move the locking member to any particular position relative to the support 17.

The support 17 being threaded on the casing 11 can readily be adjusted longitudinally thereof to position the track 60 in proper position to receive the locking member 57 which is urged into engagement with the track by the pressure of the spring 38. After the support has been adjusted to the desired position on the casing it can be secured in said position against turning by a set screw 65, the inner end of which contacts the inner end of the casing 11, as shown in Fig. 2.

It will be seen that all that is required to condition the inner tubular unit 18 for removal from the casing 11 is to push the button 61 inwardly to effect release of the locking member 57, after which the unit can be readily withdrawn from the casing, this being done without having to remove the operating lever 43 from the casing, since the reduced outer end of the tubular section 19 will not be obstructed by the part 47 of the lever which normally engages the inclined shoulder 49 of the section.

Furthermore the proper positioning of the unit 18 within the casing requires merely the

simple operation of inserting it therein and moving it longitudinally thereof until the locking part 57 is opposite the groove 59 at which time said part will be snapped into the groove by the spring 53.

It will be understood that when moving the unit 18 into position within the casing that it will be guided by the walls of the latter and that the outer end of the section 19 will become telescoped upon the tube or section 16 disposed within and fixed relative to the casing.

By mounting the unit 18 for a rotary or swiveling movement within the casing 11 the trouble ordinarily experienced by the flexible supply conduit becoming kinked or twisted when in use can readily be overcome merely by rotating the unit to remove the kinks, thus making it unnecessary to have to detach the supply conduit from the unit or to remove any of the parts of the latter.

It will be understood that in rotating the unit 18 within the casing that the inclined annular shoulder 49 of the outer tubular section 19 will be free to move in engagement with the inwardly projecting portion 47 of the lever 43 which will in no way interfere with the rotation of the unit.

It will be noted that the rotary unit 18 constitutes in effect a single tube having a continuous axially disposed passage therethrough for discharging the fluid or liquid to the nozzle, under the control of the valve. Furthermore, it will be seen that the syringe is formed of two complete self-contained units made readily separable merely by movement of a single part conveniently located on the syringe for operation by the pressure of the finger to release position, and in which construction the units can be assembled for use merely by the insertion of one within another.

It is apparent from the disclosure and the description of the syringe that the invention comprises an exceedingly convenient and practical instrument, and that the ready detachability of the units one from another contributes to avoidance of delay in assembling and disconnecting the same, which is particularly advantageous where it is desired or found necessary to separate and sterilize one or both of the units from time to time.

I claim:

1. In a syringe, a casting having a nozzle, a unit mounted within the casing independently of the nozzle and having a longitudinally extending passage for delivering the fluid to the nozzle, said unit being withdrawable from the casing and including relatively movable sections having an actuating part within the fluid passage operable by movement of one of the sections relative to another, valve means for controlling said passage responsive to said actuating part, and a releasable locking element interposed between the casing and the unit for retaining the latter within the casing, said locking element having an operating part disposed within an opening in the wall of the unit and operable through the opening to effect release of the locking element.

2. In a syringe, a casing having a nozzle thereon at its outer end, a tubular unit within the casing comprising inner and outer communicating sections, said outer section communicating with the nozzle and being enclosed within the casing and movable longitudinally therein and relative to the inner section, valve means within the casing normally closing the inner section, said valve means being operated by movement

of the outer section longitudinally within the casing in one direction, and means on the casing for moving the outer section longitudinally therein, said inner and outer sections and said valve means being removable from the casing as a unit through the inner end thereof.

3. In a syringe, a casing having a nozzle, a tubular unit rotatably mounted within the casing and comprising relatively movable sections for delivering fluid to the nozzle, valve means for controlling the flow of the fluid operated by effecting relative movement between the sections, one of said sections having an annular portion thereon, and a lever pivotally mounted on the casing and having a part projecting therein and adapted to engage said portion during rotation of the unit and to cooperate with said portion to effect relative movement between said sections upon movement of the lever in one direction, said unit being withdrawable from the casing with the lever in normal position upon the casing.

4. In a syringe, a casing having a nozzle, a tubular unit within the casing comprising relatively movable tubular sections for delivering fluid to the nozzle, said unit including valve means for controlling the flow of the fluid through the sections, means on the casing for moving one of the sections relative to another to effect operation of the valve means, said unit being withdrawable from the casing, and locking means for the unit including cooperating parts on the unit and the casing, one of which is resiliently mounted for movement automatically into engagement with the other, said locking part being releasable from the exterior of the casing to free the unit for withdrawal from the casing.

5. In a syringe, a casing having a nozzle, a unit within the casing for delivering fluid to the nozzle, comprising tubular sections one movable within the casing longitudinally of the other and having a shoulder intermediate its ends, valve means for controlling the flow of the fluid through said tubular sections responsive to said movable section when moving it to a predetermined position within the casing, operating means movable on the casing and having a part for cooperation with said shoulder to effect movement of the last mentioned section to said predetermined position, said unit being withdrawable from the casing through one end thereof, and means supporting the unit for rotation within the casing and relative to the part for actuating said movable section.

6. A dental hand instrument comprising the combination of a casing member and a tubular member telescopically mounted in said casing member said tubular member including a valve, means for coupling the casing member and tubular member together comprising quickly releasable locking parts between said casing member and tubular member, and a valve operating element extending through the casing member from the outside thereof and into engagement with the valve, said parts and said valve being so constructed and arranged that the casing member and the tubular member may be telescopically assembled when the members are in any axial relation with each other and the valve actuated when the members are in any such axial relation.

7. A dental hand instrument comprising the combination of a casing member and a tubular member telescopically and rotatably mounted in said casing member, a valve carried by said tubular member for controlling the flow of fluid there-

- through, a manually controlled valve operating element extending through the casing member, means comprising an element carried by said tubular member adapted to be engaged by said operating element when said members are in any axial relation with each other to enable operation of the valve when the members are in any such axial relation, means for coupling the casing and tubular member together comprising

quickly releasable locking parts between said casing member and tubular member, said parts being so constructed and arranged that the tubular member may freely rotate in the casing member to thereby enable the members to be assembled telescopically when the members are in any axial relation with respect to each other. 5
